STEAM JET PUMP

James Garvie, Bedford Park, London, England

Application September 9, 1932, Serial No. 632,465
In Great Britain October 20, 1931

3 Claims. (Cl. 230—95)

My present invention relates to improved means for eliminating smoke and improving thermal efficiency of boilers. Heretofore various efforts have been made to eliminate smoke and improve 5 thermal efficiency by employing steam and air blast apparatus in which a nozzle connected to a source of steam supply projects a jet of steam into a Venturi nozzle and is located within a tubular jacket or sleeve provided with air admission apertures. It is found that with apparatus of this 10 type as at present in use there is a tendency to use it as little as possible because of the excessive noise set up by the action of the steam jet within a tubular casing which generally communicates 15 with a pipe like air supply conduit the whole construction of which is such as to produce an undesirable volume of sound. Also it is found that certain boilers have different requirements as to the relative value of steam and air supply and 20 generally the rate of supply of steam is adjusted to suit the requirements of the boiler as far as possible but the regulation of the air supply is not adjusted with respect to each jet so that the desired result is not always obtained. The object 25 of my invention is to provide a construction of blast apparatus for furnaces which will not have these disadvantages.

In order that this invention may be clearly understood and readily carried into effect two 30 sheets of drawings are appended hereto illustrating embodiments thereof and wherein,

Fig. 1 is a longitudinal sectional view of one of the jets.

Fig. 2 is a side elevation view of the nozzle of 35 the device shown in Fig. 1.

Fig. 3 is a detail sectional view to a larger scale showing the device for regulating the quantity of steam flowing to the jet.

Fig. 4 is a part sectional plan view showing a 40 coupled pair of injectors.

Fig. 5 is a part sectional front elevation view showing a modified arrangement of smoke eliminators which are particularly adaptable to boilers fitted with mechanical stokers, and

Fig. 6 is a vertical sectional view of a complete 45 assembly of one of the devices shown in Fig. 5.

Referring to the drawings, the blast apparatus comprises an air conduit 1 open at one end 2 and closed by a plate 3 at the other and having directed laterally from it one or more chambers 4 each accommodating a steam jet 5 co-axially aligned with a Venturi tube 6 directed towards the furnace, the open end of the air supply conduit having disposed around it a bell shaped cap 7 and having provided within it one or more baffles 8 for the purpose of producing a form of silencer, each said jet 5 having disposed about it a cone 9 provided with one or more air supply apertures 10 each adjustable in effective area of opening.

In carrying the preferred embodiment of my

invention into practice the air conduit can as shown in Fig. 4 be composed of a number of flanged cast or drawn steel or iron tubes with flanges 11 at their ends which are bolted together to provide an air conduit of the required axial dimension, each flanged unit of this conduit having cast integral with it or welded to it a chamber 4 in the form of a cylindrical box the axis of which is at right angles relatively to the axis of the air conduit 1. By constructing the air conduit in this manner a large amount of noise is eliminated as compared with existing apparatus in which the air conduit is made of sheet metal. The plate 3 is bolted against the outer flange at such end and the other end of the conduit is composed of a tube 1a from which the box 4 and the outer flange 11 are omitted. Fitted over its outer end so as to have an annular and an axial clearance therefrom is the bell shaped cast metal cap 7 so that the air entering said cap has to reverse its direction of travel to enter the air conduit. Arranged diagonally across the interior of the air conduit at its inlet end is a baffle 8 in the form of a plate provided with a plurality of perforations as shown so that the combination of this perforated plate and annular cap provides a silencer. If required more than one of these diagonal plates can be employed, their faces being parallel with and contiguous to each other and their apertures stepped relative to each other or directly aligned with each other. Each of these said plates can be secured in position by one or more screws 12 passed through the appropriate part of the air conduit into the periphery of each plate. The bell shaped cap can be secured in position by one or more radial screws 13. Each of the said laterally directed boxes 4 formed with the air conduit 1 accommodates one of the steam jets 5 preferably co-axially mounted within the box and supported within a concentric sleeve 14 fitted in a concentric tubular boss 15 formed integral with the outer end of the box 4, this concentric boss being normally closed by a movable cover cap 16 which can be hinged at one end on a screw threaded into the outer end of the box and engaged at its other end by means of a hook shaped part over another like screw. The body of the steam jet 5 is bored axially to receive an adjustable needle 17 in well known manner and the body 5 is apertured between its periphery and its axis to provide a supplementary air passage 18. Air can pass through into an annular space 19 surrounding the support of the adjustable needle and from thence through the passage 18 formed along the said body parallel with its axis. This supplementary air can be admitted by opening the closure plate hinged at the outer end of the box. The inner end of the sleeve 14 accommodating the jet is formed with a conical part 20 terminating in a nozzle 21

directed towards a Venturi tube 22 fitted into a central aperture in the inner end of the said box, this Venturi tube being connected at its front end to a conduit 23 directed into the required zone of the furnace. This conduit may have a flared downwardly inclined nozzle 24 detachably fitted on its free end as this part is subject to burning and by such an arrangement a cheap and easy replacement is effected. Also the said flared nozzle can be composed of a metal or alloy of high heat resisting quality. Steam is admitted to the jet body by a radial pipe 25 threaded into the body 5 and carried through an opening provided for such purpose in the side of the said box 4, and for the purpose of regulating the supply of air the cone shaped front end 20 of the said sleeve is formed with a number of longitudinal slots 26 and has disposed about it the conical throttle member 9 slotted as at 10 to correspond with the slots 26 in the conical part of the sleeve and formed with a short cylindrical portion 9a at its inner end fitted over the correspondingly shaped part of the said sleeve, a set screw 27 being passed through a circumferential slot in said cylindrical portion into the said sleeve so that a fine adjustment can be effected with each jet.

When, as would normally be the practice a number of jets and their associated parts are provided a steam supply pipe 28 common to all of the jet pipes 25 is provided connected to the pipes 25 by suitable T's and elbows in well known manner.

When the invention is applied to a boiler fitted with mechanical stokers, the smoke eliminators can consist of a number of individual devices not connected to a common air conduit 1. Such an arrangement is shown in Figs. 5 and 6 in which each box 4 is formed with lugs 4a by means of which it is attached to the boiler end plate. Steam pipes 25 are carried to the jets inside the boxes 4 and each box is formed with an upstanding air conduit portion 1b on which is bolted the tubular member 1a in the same manner as previously described. In this arrangement the bell shaped members 7 are located above the steam injectors, the parts in this embodiment corresponding to those in the previously described embodiment bearing the same reference numerals. The bell shaped enclosing cap necessitates the air entering the inlet conduit following the sinuous course, and as the mouth of the bell shaped cap is in juxtaposition to the said box the induced air is to a certain extent pre-heated by being drawn over the said box before entering the air inlet conduit, it being understood that the said box will acquire a certain degree of heat by reason of the location therein of the steam jet.

The construction of device shown in Figs. 5 and 6 is intended to supply steam and air to a single nozzle and for this purpose it is preferred to provide with the steam supply pipe means whereby the effective aperture of the steam passage can be adjusted quite readily to suit the particular requirements of the furnace and the jet. This adjustment device which is also shown applied to the embodiment in Figs. 1 and 2 consists in providing a joint or coupler in the steam pipe 25 near the said box, said joint or coupler incorporating an annular nut 29 within which is located a metal disc 30 centrally apertured for the passage of steam. This metal disc can be readily replaced by one formed with a different

diameter of aperture so that a steam tight and reliable method of adjusting the supply of steam is provided which does not require expensive fittings such as control cocks or valves.

It is also found that by using a single unit in this manner a highly efficient pre-selection of steam and air can be obtained which enables the nozzle which drives the steam and air into the furnace to be so constructed that it sets up a turbulence action materially increasing thermal efficiency and the diminution of smoke. A suitable method of obtaining this turbulence is to fit in the mouth of the nozzle a number of radial webs 31 which are inclined relatively to the axis of the nozzle so as to impart a spin or whirling to the ejected steam and air.

The shape and direction of the nozzle 24 is preferably so arranged that the delivery of the column of air crosses over the delivery of air from adjacent nozzles and sets up turbulence in the furnace, and the air is pre-heated by coming in contact with the nozzles, all of which increases the efficiency of combustion.

What I claim is:

1. In a steam jet pump for delivering steam and air into a furnace for eliminating smoke, a box, an air inlet conduit extending laterally from one side of said box, a steam jet accommodated in said box, an outlet in one end of said box opposite which is located the emission end of said jet, a Venturi tube fitted in said outlet, an outer open inlet end of said air conduit, and a substantially bell shaped cap fitted over and about the said open inlet end of said conduit so as to be annularly spaced therefrom so as to provide an annular air passage about the said air conduit, a baffle in said air conduit, said bell shaped cap having an open inlet located between the ends of the air conduit, a steam and air emission tube being fitted to the outer end of said Venturi tube.

2. In a steam jet pump for delivering steam and air into a furnace an air conduit open at one end and closed at the other, a chamber intersecting said conduit and projecting laterally therefrom between its ends, a steam jet in said chamber, a Venturi tube fitted in one end of and directed from said end of the chamber towards the furnace, said jet being co-axial with said Venturi tube, a substantially bell shaped cap disposed about and spaced from the open end of said air supply conduit, and a baffle inside said air supply conduit, the bell shaped cap surrounding the said air supply conduit to provide an annular air space, a steam and air emission tube being fitted to the outer end of said Venturi tube.

3. In a steam jet pump for delivering steam and air into a furnace an air conduit open at one end and closed at the other, chambers intersecting said conduit and projecting laterally therefrom between its ends, steam jets in said chambers and Venturi tubes in one of said chambers directed from said chambers towards the furnace, said jets being coaxial with said Venturi tubes, a substantially bell shaped cap disposed about and spaced from the open end of said air supply conduit, a baffle in said air supply conduit near its open end, the said bell shaped cap surrounding the said air supply conduit to provide a substantially annular air space, and air and steam emission tubes fitted to the outer ends of said Venturi tubes.

JAMES GARVIE.
